UNITED STATES PATENT OFFICE.

RALPH C. WARNER, OF MARSHFIELD, OREGON.

BOTTLE CARRIER.

Application filed June 23, 1922. Serial No. 570,285.

To all whom it may concern:

Be it known that RALPH C. WARNER, a citizen of the United States of America, residing at Marshfield, in the county of Coos 5 and State of Oregon, has invented new and useful Improvements in Bottle Carriers, of which the following is a specification.

The object of the invention is to provide a simple and efficient construction of bottle 10 carrier particularly adapted for use in connection with wide mouth bottles such as those employed for milk and similar commodities as a means of facilitating the transportation thereof; and with this object in view the invention consists in a construction and combination of parts of which a preferred embodiment is shown in the accompanying drawings, wherein:—

Figure 1 is a side view of a carrier constructed in accordance with the invention.

Figure 2 is a plan view of the carrier detached.

Figure 3 is a similar view of the band alone.

Figure 4 is a similar view of the latch alone.

The device consists essentially of a band or ring 10 adapted for embracing the neck of a bottle 11 beneath the lip or rim 12 thereof, said band in the construction illustrated consisting of a sufficiently stout wire provided at diametrically opposite points with coils 13 for engagement by the terminals of a bail 14 which may be arranged in spanning relation with the top of the bottle to serve as a means of carrying the same or may be folded downwardly to expose the top of the bottle so that the contents of the latter may be discharged without coming into contact 30 with the bail. Connecting the extremities of the band which are provided with coils forming eyes 15 and 16 is a latch 17 which is provided with terminal and intermediate eyes 18 and 19 for respective engagement 35 with the terminal eyes 15 and 16 of the band so that by a swinging movement of the latch the terminals of the band may be brought into overlapping relation to contract the band upon the neck of the bottle whereas by a 40 swinging movement of the latch in the opposite direction the band may be expanded to facilitate moving the same over the terminal

bead or lip 12 in applying or removing the same from the bottle. The latch at its free end is provided with a loop forming a finger 55 hold 20 and in addition thereto the extremity of the blank forming the latch is deflected to provide a finger 21 adapted to engage an eye 22 consisting of a further coil of the band to hold the latch in its band contracting 60 position. To expand the band so as to apply it to the bottle or remove it therefrom the finger 21 should be disengaged from the eye 22 and swung in the direction indicated by the arrow in Figure 1, and after having positioned the band on the neck of the bottle a swinging movement of the latch in the opposite direction will contract the band whereupon the finger 21 may be reengaged 65 with the catch eye 22 to lock the band in 70 place.

Having described the invention, what is claimed as new and useful is:—

1. A bottle carrier having a band of variable diameter provided with means for the attachment of a bail and having terminal eyes, and a latch having terminal and intermediate eyes respectively engaging the terminal eyes of the band and movable relative to the band to expand or contract the latter, said band and latch consisting of blanks of wire with the latter provided at its free end with means for engagement with the band to hold the latch in its band contracting position.

2. A bottle carrier having a band of variable diameter provided with means for the attachment of a bail and having terminal eyes, and a latch having terminal and intermediate eyes respectively engaging the terminal eyes of the band and movable to expand or contract the latter, said band and latch consisting of blanks of wire with the latter provided at its free end with a loop forming a finger hold with the extremity of the blank deflected to form a catch finger for interlocking engagement with the band to hold the latch in its band contracting position.

3. A bottle carrier having a band of variable diameter provided with means for the attachment of a bail and having terminal eyes, and a latch having terminal and intermediate eyes respectively engaging the ter-

5 minal eyes of the band and movable to expand or contract the latter, said band and latch consisting of blanks of wire with the latter provided at its free end with a loop forming a finger hold with the extremity of the blank deflected to form a catch finger for interlocking engagement with the band to

hold the latch in its band contracting position, one of the latch eyes being open to permit of disengagement thereof to separate the 10 extremities of the band.

In testimony whereof he affixes his signature.

RALPH C. WARNER.
